UNITED STATES PATENT OFFICE

RICHARD H. JEFFERIES, OF RICHMOND, VIRGINIA

CIGARETTE EXTINGUISHER

Application filed March 21, 1930. Serial No. 437,675.

My invention relates to smokers' accessories, and particularly to extinguishers for cigarettes.

It is the habit of many smokers after lighting a cigarette to take a few whiffs, and then to put it down, to go on with their dressing, or work, or reading, or card playing; to take the cigarette up again a minute or so later; but often forgetting it until it has burned down to and has charred the surface upon which it is resting.

The object of my invention is to provide a device in which the cigarette may be held; and in which the cigarette may be allowed to burn down to a predetermined point; at which point it will be extinguished.

A further object is to provide a device of this class which may be carried in the pocket and which may be readily attached to some available support.

In the drawing: Fig. I shows my device in plan; Fig. II is a perspective view of the same.

Referring to Figs. I and II a metal plate 25 or tray 1 is mounted on a stem 2; and hinged at one end of the metal plate is the metal rod 3; so placed with reference to the length of the plate 1, that upon a cigarette being placed on the plate, the rod when dropped will lie across the end of the cigarette just behind the burning end. To the lower end of the stem 2 may be attached a screw 4, for permanent insertion into woodwork; or the attaching means may be in the form of a clip to clip over the edge of any structure; or it may be in the form of the well known rubber sucker by which the device may be attached to any even and flat surface.

The end of the plate 1 does not project beyond the rod 3, but is cut back, as shown in Fig. II, so that the edge of the plate 5 is practically in the same vertical plane as the rod 3; the upper edges or flanges 6 of the plate extending beyond the bottom edge to form 45 the hinge 7; and the rest 8.

Instead of hinging the rod 3, the said rod may be merely dropped into slots formed in the opposite sides of the plate 1; the object of the slots being to hold the rod against displacement. But the hinged form is to be preferred, since it prevents the loss of the rod. When it is desired to use the extinguisher, the smoker tips back the rod 3 with his finger, places the cigarette in the desired position on the plate, and then with his finger drops the 55 rod 3 upon it, adjusting the position of the cigarette so that it will be extinguished at the desired point. Other forms of extinguishers have been made, but in them the cigarette has been promptly extinguished; 60 whereas in my extinguisher it is possible for the smoker to allow the cigarette to continue to burn for a predetermined length of time; so that if he wishes to take it up and continue smoking before that time has elapsed, he will 65 find the cigarette still burning. On the other hand if he forgets it it will be extinguished.

In several other forms of cigarette extinguishing holders the body of the cigarette is tightly nipped between two prongs or 70 members; and this nipping of the cigarette closes the air spaces between the shreds of tobacco, so preventing the passage of air. The cutting off of this draft causes the lighted cigarette to go out more quickly than it 75 would if the air passages through the cigarette were not closed. In my cigarette holder and extinguisher it will be noted that the rod 3 merely lies upon the body of the cigarette, and that the pressure it exerts upon the cigarette is only that due to the weight of the rod. The cigarette continues to burn until the fire arrives at the rod. The fire then dies out. The smoker who desires 80 to resume smoking upon his cigarette places it in the tray with a sufficient length projecting beyond the rod to prevent it being extinguished before he is ready to take it up again. 85 90

I claim:—

A cigarette holder and extinguisher consisting of a supporting member; a tray mounted upon the supporting member; and a metal rod hingedly connected to the tray and arranged to lie upon a cigarette on the tray with a light pressure but one insufficient to close the air passages through the cigarette.

In testimony whereof I have hereunto affixed my signature.

RICHARD H. JEFFERIES.
